FIG.3

APPARATUS FOR APPLYING A SUBSTANTIALLY CONSTANT TENSION TO AN ELONGATED MEMBER CONNECTED TO AN INSTALLATION SUBJECT TO ALTERNATING MOVEMENTS

The present invention relates to an apparatus for applying a substantially constant tension to an elongated member connected to an installation subjected to alternating movements.

More particularly, but not limitatively, the invention relates to an apparatus for supporting, with a substantially constant force, an elongated member suspended from an installation subjected to vertical movements.

There will be contemplated, by way of non limitative example, such operations as off-shore drilling operations performed from a floating installation, from which is suspended for example, an elongated member such as a drill string.

During these operations the drill string must be kept under a substantially constant tension, so as to be unaffected by the vertical movements of the floating installation.

The upper end of the drill string is generally connected to a hook carried by a travelling block which is suspended, by a cable used for handling the drill string, from a stationary crown block, located at the top of a derrick carried by the floating installation.

In order to automatically compensate for the vertical movements of the floating installation, it has been proposed to make use of a hydraulic jack fixed at one of its ends to the top of the derrick and supporting the stationary crown block, this jack extending with its longitudinal axis along the direction of displacement of the floating installation, i.e., along a substantially vertical direction.

An automatic compensation for the movements of the floating installation is obtained by supplying the jack with fluid under pressure delivered by an oleopneumatic (oil-and-gas) accumulator.

When, as a result of the vertical movements, the piston is displaced within the cylinder of the jack, the pressure in the accumulator varies according to a polytropic law :

$$P V^{\kappa} = \text{constant}$$

It can be shown that, as a first approximation, the volume variations ΔV_o and pressure variations ΔP_o of the mass of gas contained in the accumulator, resulting from the vertical movements of the floating installation, are defined by the relationship :

$$\Delta P_o / P_o = K \Delta V_o / V_o$$

In the above formula P_o is the initial gas pressure in the accumulator which is the same as that of the fluid contained in the jack, whereby a tension force can be exerted on the drill string, V_o is the volume of the pressurized gas and K a coefficient which depends in particular on the type of gas housed in the accumulator.

For a maximum acceptable variation of 10 percent for example in the tension exerted on the drill string, corresponding to a variation of 10 percent of the pressure in the jack, there must be used an accumulator having a volume V_o such that

$$V_o \geq 10 K \Delta V_o$$

In practice, since the choice of the pressure P_o is determined by the design requirements for the accumulator

and the jack and by the amplitude of the vertical movement of the floating installation, there must be used accumulators of great volume V_o which are very expensive and bulky on the floating installation.

- 5 It has therefore been proposed to add to the vertical jack, one or several inclined jacks, each having one end articulated on the derrick and the other end supporting the stationary crown block. By using such jacks inclined with respect to the travel path of the stationary 10 crown block (path relative to the floating installation) there can be obtained a better regulation in the tension exerted on the drill string and it becomes possible to substantially reduce the overall volume V_o of the accumulators. The drawbacks of such devices consist, on 15 the one hand, in the fact that the volumes V_o required for the accumulators are still rather great and, on the other hand, that the heavy weight of the jacks fixed at the top of the derrick is detrimental to the stability of the floating installation and creates high dynamic 20 stresses in the derrick.

An object of the present invention is accordingly to suppress or at least to reduce the drawbacks of the prior devices, by providing a device for keeping a working fluid under substantially constant pressure, this device being, in particular, suitable for use in apparatuses for keeping an elongated member under a substantially constant tension.

The apparatus according to the invention, for applying a substantially constant tension to an elongated member connected to an installation subjected to alternating movements, comprises in combination :

- 30 a. means for applying a force to the elongated member, including at least one main jack,
 b. regulating means, on the installation, for supplying a working fluid under a determined pressure, this fluid being supplied to said main jack; this regulating means being interposed between the cylinder of said main jack and a source of at least one pressurized fluid, said source containing a gas whose pressure varies with the volume occupied by the gas, this regulating means comprising at least one group of jacks, an element of at least one jack of said group being connected through a moveable articulation to an element of at least another jack of said group the element of at least one jack of said group which is not connected to said moveable articulation being rotatably mounted on a fixed point of the installation, said moveable articulation being compelled to move along a predetermined path, fixed with respect to the installation, said fixed point being so located that the axis of said rotatable jack remains inclined on said path during the rotation of said rotatable jack, at least one jack of said group being fed with pressurized fluid from said source, and at least one jack of said group being connected to the cylinder of said main jack through a pipe containing an incompressible fluid.

One of the advantages of the device according to the invention is to provide an apparatus applying a substantially constant tension to a drill string suspended, through handling means, from the top of a derrick integral with a mobile installation whose heavy constituting elements are not located at the top of the derrick, so as to improve the stability of the mobile installation.

Other advantages will appear from the following description illustrated by the accompanying drawings, showing a non-limitative embodiment of an apparatus

according to the invention for keeping substantially constant the tension exerted on a drill string suspended from an installation for off-shore drilling.

FIG. 1 is an overall view of this apparatus,

FIGS. 2 and 3 respectively show the variation in the pressure applied to the main jack and in the tension exerted on the drill column, as a function of the displacements of the piston of this jack, under the action of the vertical movements of the floating installation.

Reference numeral 1 indicates the floating installation topped by a derrick 2. A drill string (not shown) is suspended from the floating installation through handling means constituted, in this particular embodiment, by a hook 3 integral with a travelling block 4 suspended by a cable 5 from a crown block 6. The cable 5, used for handling the drill string, passes over a device, which forms no part of the invention, constituted by articulated arms 7 and 8 and pulleys 9 and 10, for preventing wear of the cable which might result from friction on the crown block.

The crown block 6 is suspended from the end of the stem of a supporting jack 11 fixed to the derrick 2 and constituting the means for supporting the drill string.

This jack is placed substantially in line with the direction of the vertical movements of the floating installation, i.e. along a substantially vertical direction. The jack 11 is connected through a pipe 12 to a regulating device. This device produces a force, in the manner indicated hereinafter, so as to keep under a determined pressure the working fluid supplied to the jack 11.

The elements constituting the regulating device have been shown in a vertical position for the clarity of the drawing, but this arrangement is not limitative. The device comprises a first jack 14 having one of its constituting elements for example its cylinder pivotally articulated at one end thereof about a fixed point 15. A point of its second constituting element, for example the point 18 of the stem of the jack, is compelled to move along a determined path 19, so that the axis of the jack 14 has an inclination angle α along the path 19.

A pipe 20a connects the jack 14 to an accumulator 20 containing an invariable mass of gas. This accumulator 20 is for example an oleopneumatic accumulator whose pressure varies with the relative displacement of the elements constituting the jack 14 when point 18 moves along the path 19.

The path 19 has been so determined that the variations in the inclination α of the jack 14 along the path 19 corresponding to the displacements of the point 18 result in a variation of the ratio of the force exerted by the jack to the component of this force along this path which substantially provides for some compensation of the pressure variations of the fluid in the jack 14.

As a matter of fact, when considering the device in the position shown in the drawing, as the point 18 moves toward the point H of the path 19, the pressure in the jack 14 decreases, thereby producing a corresponding decrease in the force exerted by the jack 14 on the point 18.

Correlatively, the angle α decreases and the component along the path 19 of the force exerted by the jack 14 on the point 18 undergoes relatively small variations.

When the point 18 moves toward the point B of the path 19, the pressure in the jack 14 increases, which results in an increase of the force exerted by the jack 14 on the point 18.

Correlatively the angle α increases and the component along the path 19 of the force exerted by the jack 14 on the point 18 undergoes relatively small variations.

5 The regulating device is connected to means for converting the component along the path 19 of the force exerted by the jack 14 into a determined pressure P_u .

These converting means consist of an intermediate jack 16, whose constituting elements, for example the 10 stem of the jack 16, is connected to the point 18, the other constituting element, for example the cylinder of the jack 16, being integral with a fixed supporting point 17.

In the drawing the cylinder of the jack 16 is articulated about its fixed supporting point 17 and the axis of 15 the jack 16 makes an angle β with the path 19, this angle β varying with the displacements of the point 18 on the path 19.

It will be obviously possible, without departing from 20 the scope of the invention, to place the jack 16 with its axis along the path 19.

By this way, the stem of the jack 16 is subjected to the action of the component along the path 19, of the force exerted by the jack 14, which maintains under a 25 determined pressure the fluid which is contained in the jack 16 and conveyed to the supporting jack 11 through the pipe 12.

The pressure P_u supplied by the jack 16 and the pressure P in the accumulator 20 are interrelated through 30 the relationship :

$$P_u = P(S/S) (\cos \alpha / \cos \beta) \quad (1)$$

The values of this pressure which correspond to the 35 limit positions (B and H) of the moveable articulation 18 in the guideway 19 (FIG. 1) are respectively :

$$P_{uB} = P_B (S/S) (\cos \alpha_B / \cos \beta_B) \quad (2)$$

40

$$\text{and } P_{uH} = P_H (S/S) (\cos \alpha_H / \cos \beta_H) \quad (3)$$

45

wherein the indexes B and H indicate the particular values of the different parameters P_u , P , α and β of the relation (1), corresponding to the respective positions B and H of the moveable articulation 18.

In practice, it is sufficient to choose the limit values 50 P_{uB} and P_{uH} of the desired working pressure P_u which has to be supplied by the jack 11 for the limit positions of the moveable element of the jack 11 (these values P_{uB} and P_{uH} being, or not, different).

The values P_{uB} and P_{uH} will be selected as a function of the particular conditions of each considered case of utilization.

In the contemplated embodiment wherein this pressure is used in a main or supporting jack 11 in order to control the tension T applied to a drill column, the values of P_{uB} and P_{uH} will for example be determined with 60 consideration of the influence of a system of pulleys interposed between the drill column and the supporting jack 11.

Test values are selected for the construction parameters of the regulating system, these parameters being 65 (FIG. 1) the values of d_{14} and d_{16} (respective distances of the articulation points 15 and 17 from the axis of the guideway 19), the limit values α_H , α_B and β_H , β_B of the

angles α and β and the values of the respective cross-sections S and S of the jacks 14 and 16 respectively.

By application of the relationships (2) and (3) it can be deduced from the values selected for P_{u_B} and P_{u_H} the values P_B and P_H of the pressure of the auxiliary fluid in the accumulator 20, as a function of the values α_B , α_H , β_B and β_H (FIG. 1) which have been selected.

The determination of the values of P_B and P_H makes it possible to calculate the volume which is necessary for the accumulator 20.

As a matter of fact, the pressure P in this accumulator varies substantially according to a physical law having the form : $PV^K = \text{constant}$, wherein K is a coefficient whose value depends, in particular, on the nature of the pressurized gas and V is the volume of gas at the pressure P of the accumulator 20, applied to the piston of the jack 14.

There results therefrom the relationship :

$$P_H V_H^K = P_B V_B^K \quad (5)$$

wherein V_B and V_H are the values of the volume of pressurized gas when the position of the moveable articulation 18 is respectively at point B and point H of the guideway 19.

Letting $V_H - V_B$ be defined as ΔV ; there results from the relation (5) :

$$V_B = \Delta V / (P_B / P_H)^{1/K} - 1$$

The value of ΔV is known, since it is equal to the product of the cross-section S of the jack 14 by the stroke of its piston when the moveable articulation 18 is displaced between points B and H, V_B being the minimum value of the volume of pressurized gas.

The nominal volume of the accumulator 20 can thus be determined since the values of P_B and P_H have already been determined (the calibrating pressure of this accumulator is substantially equal to P_B).

Thereafter can be plotted, in the manner to be indicated hereinunder, the curve

$$T = F(h) \quad (6)$$

representing the variations in the tension T applied to the drill column, as a function of the displacement h of the main jack 11 from its lowermost position.

To each value of h corresponds a well defined position of the moveable articulation 18 along the guideway 19, i.e., well defined values for the angles α and β , when the values β_H , β_B , d_{16} and S have been fixed.

As a matter of fact, to the displacement h of the piston of jack 11 from its lowermost position corresponds a determined variation of the volume of hydraulic fluid in the cylinder of jack 16 through the pipe 12 (at any moment the displacements of the pistons of the jacks 11 and 16 from their initial position (lowest position), represent the same percentage of their maximal stroke).

In this position of the moveable articulation 18, to which corresponds a determined position of the piston of the jack 14, the gas at the pressure of the accumulator 20 occupies the volume $V_B + \delta V$ and its pressure P is defined by the relation :

$$P_B V_B^K = P(V_B + \delta V)^K$$

$$\text{hence } P = P_B (V_B / V_B + \delta V)^K \quad (7)$$

It is thus possible to determine the pressure P for each value of h to which corresponds a well-defined value of each of the angles α and β .

For each so-obtained value of P is determined the corresponding value of P_u using the above-indicated relation :

$$P_u = P(S/S) (\cos \alpha / \cos \beta)$$

and there is deduced the corresponding value of the tension T which, in the embodiment illustrated by way of example, depends on the influence of the pulley or block system.

The graphs of FIGS. 2 and 3 show respectively the variations of P_u (expressed in kg/cm²) and T (expressed in tons), as a function of the stroke h (expressed in meters) of the piston of jack 11, obtained in accordance with the following data :

horizontal distance between the axes of pulleys 9 and 10 and the axis of pulley 6 when the latter is in its lowermost position = 3.3 meters,

vertical distance between the axes of pulleys 9 and 10 and the axis of pulley 6 when the latter is in its lowermost position = 1.8 meters,

The cable 5 forms 12 turns between the pulley 6 and the moveable block or pulley system 4.

maximum stroke h_M (FIG. 1) of the main jack 11 determined by the amplitude of the vertical movements of the floating installation = 4.6 meters.

Moreover the following data have been selected :

$$d_{14} = 3.30 \text{ meters}$$

$$d_{16} = 3.90 \text{ meters}$$

$$\beta_H = 41^\circ$$

$$\beta_B = 20^\circ$$

In the graphs of FIGS. 2 and 3 the curves in dotted lines show the variations obtained for P_u and T respectively when choosing :

$$\alpha_H = 23^\circ$$

$$\alpha_B = 45^\circ$$

The curves in solid lines show the results which are obtained with the following newly selected values :

$$\alpha_H = 26^\circ$$

$$\alpha_B = 50^\circ$$

The curves in dot and dash lines are the ideal curves to which the actual curves have to be brought as near as possible.

It is thus possible to optimize the system by selecting for the parameters of construction: 60_H , β_H , d_{14} , S and β_B , β_H , d_{16} and S , the values corresponding to the test curve of the pressure P_u which is nearer the curve in dot and dash line representing the desired values of this pressure P_u , in this particular embodiment, chosen in order to obtain the variations of the force exerted by the jack 11 which makes it possible to keep substantially constant the tension T applied to the drill column.

It should be noted that on the graph of FIG. 3 the scale of the ordinates has been considerably amplified, the relative variations in the tension T of the drill column not exceeding ± 1.5 percent.

It will obviously be possible to select differently the limit values P_{u_B} and P_{u_H} of the pressure, to comply with different conditions of use and for example as a consequence of a different value of the tension T .

This can be achieved by a modification of the mass of fluid in the accumulator 20, for example by actuating on the valve 20b (FIG. 1).

What we claim is :

1. An apparatus for applying a substantially constant

tension to an elongated member connected to an installation subjected to alternating movements, which comprises a combination:

- a. means for applying a force to the elongated member, including at least one main jack,
- b. regulating means on the installation, for supplying a substantially incompressible working fluid under a determined pressure, this fluid being supplied to said main jack, this regulating means being interposed between the cylinder of said main jack and a source of at least one pressurized fluid, said source containing a gas whose pressure varies with the volume occupied by the gas, this regulating means comprising at least one group of jacks, an element of at least one jack of said group being connected through a moveable articulation to an

5

10

element of at least another jack of said group, at least one jack of said group having one element not connected to said moveable articulation and rotatably mounted on a fixed point of the installation, said moveable articulation being compelled to move along a predetermined path, fixed with respect to the installation, said fixed point being so located that the axis of said jack having a rotatably mounted element remains inclined on said path during rotation of said jack having a rotatably mounted element, at least one jack of said group being fed with fluid at the pressure of said source, and at least one jack of said group supplying the cylinder of said main jack with said incompressible fluid at a determined pressure different from that of the source through a pipe.
